UNITED STATES PATENT OFFICE.

ALBERT MARION FERGUSON, OF STE. CUNÉGONDE, AND JOSEPH A. U. BEAUDRY, OF MONTREAL, CANADA.

CAR-FENDER.

SPECIFICATION forming part of Letters Patent No. 706,041, dated August 5, 1902.

Application filed November 14, 1901. Serial No. 82,263. (No model.)

To all whom it may concern:

Be it known that we, ALBERT MARION FERGUSON, mechanic, a citizen of the United States, residing at No. 115 Coursol street, of 5 the city of Ste. Cunégonde of Montreal, and JOSEPH ALPHONSE UBALDE BEAUDRY, civil engineer, of the city of Montreal, in the Province of Quebec, Canada, have jointly invented certain new and useful Improvements in 10 Street-Car Fenders; and we do hereby declare that the following is a full, clear, and exact description of the same.

Our invention relates to street-car fenders. Its object is to produce a safe and reliable 15 car-fender at a moderate price.

It consists in a frame made of iron tubing and a netting of thin metal bands, the frame, in two sections, folding in a compass-joint. One of the said sections is attached to the 20 car and the other is suspended by chains to the horizontal rod, easily worked by the motorman, and when released the fender rests on two wheels running on the rails.

In the drawings attached hereto, Figure 1 25 is a side view of the fender as it appears in front of a street-car. The plain lines show the fender suspended about a foot over the roadway by chains attached to a horizontal rod. The dotted lines show the same fender 30 as let down and rolling on the rails in case of accident. Close to the splash-board is the fender folded up, if so desired. Tied to the splash-board, to the forward part of the fender and to the two suspended chains, is attached a net of fabric Q, offering a baggy 35 surface to receive the bodies of persons or things picked up by said fender. Fig. 2 is a view of the outer face of a street-car splash-board, showing the vertical rod J, its two 40 branches K K, the horizontal rod I resting on the open hooks H H. Fig. 3 is a plan of the fender stretched out and suspended by the chains E E to the horizontal rod I. It shows the netting of metal bands filling the 45 field of the fender and also the net of fabric Q stretched above the metal bands.

A is the platform of a street-car. B is the splash-board of the same.

C and D show the fender, composed of a 50 frame of gas-tubing, in two sections articulated at F in a compass-joint, the rear section

D resting in the hooks G G, fastened to the platform, where it is secured by a pin, while C, the forward section covered with rubber, is made to roll on the rails on two small rubber-tired wheels. A netting made of metal bands fills the field of the fender. 55

E are chains suspending the forward section C of the fender to the ends of the horizontal rod I. 60

F F are the compass-joints of the two sections C and D of the fender.

G G are hooks fixed to the front of the car to hold the hind section of the fender to the car. A pin put through holes in the hooks 65 prevents the fender from jumping out of its place.

H H are two open hooks attached to the upper front corners of the splash-board B to receive the horizontal rod I. 70

I is a horizontal rod resting in the open hooks H H. At each extremity of it are the metal chains E E, suspending the forward section of the fender C about a foot from the ground when the car is in use. It also carries two small chains R R, attached to the top of the splash-board B to prevent the said horizontal rod from falling out of reach of the motorman when the fender is let down in case 75 of accident. 80

J is a movable vertical rod to release the horizontal rod I from its hooks H H. It branches out in two opposite directions K K toward the extremities of the horizontal rod I. The upper ends L L of these branches 85 K K are L-shaped to fit under the horizontal rod I. It slides up and down in two collars O O. It is provided at about thirty inches from the floor with a handle N, projecting in four or five inches through the splash-board 90 B. The foot of this vertical rod J rests on the end of a pedal-lever M, placed on the floor of the platform A.

K K are the two branches of the vertical rod J, extending right and left to the ends of 95 the horizontal rod I.

L L are the two L-shaped hooks at the end of the two branches K K to lift the horizontal rod I out of its open hooks H H to release the fender and allow the same to roll on the rails. 100

M is the pedal-lever on which the foot of the vertical rod J is resting.

N is a handle in the vertical rod J, projecting through the splash-board B within easy access of the motorman.

O are two collars through which the vertical rod J slides upward or downward.

P are the two rails of the track.

Q is the landing-net, of fabric, fastened to the splash-board, to the forward section C of the fender, and along the two suspending-chains E E, Fig. 3. It shows the manner in which the said net of fabric is stretched to protect bodies of persons or things from knocking against the metal bands of the fender or against the splash-board B.

15 R R are the two small chains attached to the ends of the horizontal rod I and to the splash-board B to prevent the said horizontal rod I falling out of the reach of the motorman.

W W are two rubber-tired wheels, of three inches diameter, supporting the forward end of the fender.

The letters C, D, E, F, and I show the fender as it is usually carried in front of the cars. The letters C', D', E', F', and I' indicate the 25 fender let down in case of accident. The letters C'' D'' E'' F'' show the position of the fender folded up against the splash-board when necessary.

To use our invention, the car-fender is hung 30 on the hooks G G at the foot of the splash-board B and the horizontal rod I placed on the open hooks H H, thus suspending by the chains E E the fender's forward section C about one foot from the ground, and the invention is ready for use. In case of accident 35 the motorman gives to the vertical rod J an upward pull, either by the handle N or by pressure of the pedal-lever M, thus throwing the horizontal rod I off the two hooks H H, causing the forward section C of the fender

to fall till the two rubber-tired wheels W W rest on the rails P P and roll on them close to the ground and ready to pick up any body along its path. The two chains R R, attached to the end of the horizontal rod I and to the 45 upper part of the splash-board B, will prevent the said horizontal rod I from falling out of reach of the motorman. When the danger is over, the motorman takes the horizontal rod I with his two hands and replaces it on the 50 two open hooks H H, and the fender is again ready for an emergency.

When so desired, the fender C D can be folded up and hooked close to the splash-board B, as shown by C'', D'', and F'' in Fig. 1. 55

We will not claim as our invention iron tubing nor metal bands nor rubber-tired wheels; but

What we claim as our invention, and desire to secure by Letters Patent, is—

In safety car-fenders: a frame of iron tubing in two sections articulated in compass-joints, hooks to attach the same to cars, two rubber-tired wheels to roll on the rails, a netting of metal bands, chains to suspend said fender 65 to a horizontal rod chained to the splash-board and supported on hooks, a landing bagging-net of fabric fastened on its four sides, two supporting-chains, a vertical rod branching to the ends of the horizontal rod, for the purpose 70 and in the manner hereinabove described.

In witness whereof we have hereunto set our hands, at Montreal, November 12, 1901, in presence of two witnesses.

ALBERT MARION FERGUSON. [L. S.]
J. A. U. BEAUDRY. [I. S.]
